Rock-Ola Manufacturing Corporation, Chicago,
Ill., a corporation of Delaware

Application September 15, 1948, Serial No. 148,589

Term of patent 14 years

(Cl. D34—3)

To all whom it may concern:

Be it known that I, Chauncey E. Waltman, a citizen of the United States and a resident of Chicago, in the county of Cook and State of Illinois, have invented a new, original, and ornamental Design for a Game Table, of which the following is a specification, reference being had to the accompanying drawing, forming a part thereof.

Fig. 2 is an end elevational view as seen from either end of the table of Fig. 1; and

Fig. 3 is a side elevational view of one end of the table.

I claim:

The ornamental design for a game table, substantially as shown.

CHAUNCEY E. WALTMAN.
